(57) **CLAIM**

The ornamental design for an autonomous mobile robot, as shown and described.

DESCRIPTION

FIG. 1 is a front and top perspective view of an autonomous mobile robot showing the design;
FIG. 2 is a rear and bottom perspective view of the design of FIG. 1;
FIG. 3 is a left side elevational view of the design of FIG. 1;
FIG. 4 is a front elevational view of the design of FIG. 1;
FIG. 5 is a right side elevational view of the design of FIG. 1;
FIG. 6 is a rear elevational view of the design of FIG. 1;
FIG. 7 is a top plan view of the design of FIG. 1;
FIG. 8 is a bottom plan view of the design of FIG. 1;
FIG. 9 is a front and top perspective view of an autonomous mobile robot showing an alternative embodiment of the design;
FIG. 10 is a rear and bottom perspective view of the design of FIG. 9;
FIG. 11 is a left side elevational view of the design of FIG. 9;
FIG. 12 is a front elevational view of the design of FIG. 9;
FIG. 13 is a right side elevational view of the design of FIG. 9;
FIG. 14 is a rear elevational view of the design of FIG. 9;
FIG. 15 is a top plan view of the design of FIG. 9; and,
FIG. 16 is a bottom plan view of the design of FIG. 9.
The broken lines in the drawings depict unclaimed environmental subject matter.
